UNITED STATES PATENT OFFICE.

NATHANIEL C. STAMPS, OF OCEAN PARK, CALIFORNIA.

CARBURETER.

1,030,343.

Specification of Letters Patent. Patented June 25, 1912.

Application filed February 13, 1911. Serial No. 608,392.

To all whom it may concern:

Be it known that I, NATHANIEL C. STAMPS, a citizen of the United States, residing at Ocean Park, in the county of Los Angeles and State of California, have invented new and useful Improvements in Carbureters, of which the following is a specification.

This invention relates to improvements in carbureters for use in connection with gas engines, and is particularly adapted to use in connection with automobile gasoline engines, being adapted to feed a proper mixture of air and gasoline as required by the operation of the engine.

15 It is an object of the invention to provide a carbureter mechanism in which the inflow of gasoline is capable of being augmented by the suction of the engine, in accordance with the demands made for gaseous mixtures in speeding up the engine.

It is a further object of the invention to provide a needle valve for regulating the inflow of gasoline which coöperates with the inflow of air produced by the suction of the 25 engine.

In the accompanying drawing forming a part of this specification, Figure 1 is a side elevation of the improved carbureter embodying the features of the present invention. Fig. 2 is an edge elevation of the same taken at right angles to the view of Fig. 1. Fig. 3 is a vertical central sectional view taken through the carbureter upon the plane of the axis of the throttle valve. Fig. 4 is 35 a similar vertical central sectional view taken through the valve mechanism, but at right angles to the plane of the section in Fig. 3. Fig. 5 is a detail sectional view of a portion of the float chamber of the carbureter, showing the valve controlled by the float. Fig. 6 is an enlarged detail sectional view of the said valve which is controlled by the float. Fig. 7 is an enlarged detail view in side elevation of the needle portion 40 of the valve which supplies gasoline to the mixing chamber. Fig. 8 is an enlarged detail sectional view of the lever which connects the needle valve mechanism with the controlling mechanism of the air supply.

50 Referring now more particularly to the parts of the device, reference being had to the accompanying drawing, the features of the invention will now be described with respect thereto and in the said drawing, 1 indicates a float chamber, 2 a mixing chamber, 55 and 3 a priming receptacle or pan. The

float chamber is of any usual or ordinary construction and is preferably made in an elongated rectangular form as shown in the drawing, and is connected with a gasoline supply as at 4, the gasoline being introduced into a small chamber 5 in one corner of the float chamber. The walls of the chamber 5 are provided with an aperture, surrounding which is a valve seat 6, which is adapted to be closed by a float controlled valve 7. Said valve 7 comprises a rod as 8 having a beveled seat engaging end as 9, the said rod passing upwardly through a sleeve 10 in which it is adapted to be adjusted, the said 60 rod having a screw threaded portion at 11 by which it may be moved to different positions with respect to the said sleeve 10 by turning the upper end thereof. The said upper end of the rod is provided with a 65 milled head 12 by which it may be turned and a lock nut 13 mounted upon the rod and adapted to engage the upper end of the sleeve 10 is employed for securing the parts in the plates after they have been adjusted. 70 The sleeve 10 projects through a suitable packing gland as 14 in the top wall of the float chamber so that the milled head 12 and the lock nut 13 are outside of the float chamber and can be easily reached for adjusting 75 the parts.

Within the float chamber 1, a float 15 of ordinary construction is arranged, said float being carried by a lever 16 which is pivoted within the float chamber at 17. The outer end of the lever 16 is bifurcated as at 18 and engages parallel annular flanges 19, formed upon the outer periphery of the sleeve 10. The float is thus capable of raising or lowering the valve to admit a required quantity of gasoline to the float chamber in the usual way. The float chamber is generally provided with a glazed window or inspection opening as shown in section at the right hand side of Fig. 3.

From the lower end of the float chamber an extension depends a sufficient distance to connect with a passage 20 formed in a projection 21 extending from the float chamber which carries the priming pan 3. Extending upwardly from the central portion of the priming pan 3 is a needle valve mechanism the fixed inner tubular portion 22 of which is secured in the outlet of the passage 20 and is thus arranged in the center of the 110 pan 3 as clearly illustrated in Fig. 3. The upper end of the said tubular portion 22 ex-

tends into the lower part of the mixing chamber casing 2. Movable mounted on the said tubular member 22 is a needle carrying sleeve 23 which loosely fits upon the member 22 and is provided at its upper end with a yoke extension 24 extending some distance beyond the tubular portion of the sleeve and carrying a depending needle as 25 adapted to extend downwardly into the open end of the tubular member 22. The needle 25 is tapered so that when it is lifted from the end of the tube 22 a greater quantity of gasoline can flow from said tube than when the needle is depressed.

15 The needle is preferably made so as to not quite close the end of the tube and thus a small quantity of gasoline can always be drawn through the needle valve mechanism for starting the engine and running it at a low speed. When the engine runs at a high speed the needle valve is lifted by means of a mechanism connected with the air supply for the carburetor, as will be hereinafter fully described. Above the pan 3 and with ample space between it and the said pan for the entrance of all the air supply that will be required in the mixing chamber, is a depending cylindrical casing 26 which is secured into the lower open end of the mixing chamber 2. The upper end of this casing 26 is formed with an annular beveled valve seat 27 upon which rests a movable air controlling member or thimble 28. The said thimble 28 is provided with a flaring upper end, the outer beveled surface thereof being adapted to fit upon the seat 27 for closing the air supply at that point. The central portion of the thimble is open from end to end and the elongated body portion thereof 35 is cylindrical in form, so as to fit within a cylindrical sleeve bearing 29 spaced within the casing 26. The central portion of the thimble is somewhat contracted interiorly for a portion of its length to fit closer upon the needle valve than the other portions of the thimble. A sufficient air space is left, however, at its contracted portion, and around the needle valve, to admit a proper amount of air through the thimble to mix 40 with the gasoline introduced, for starting and running the engine at a low speed. An annular passageway is formed between the casing 26 and the inner sleeve bearing 29 through which additional air can be supplied to the mixing chamber 2, when the thimble 28 is lifted up from the seat 27. The space between the said casing 26 and the sleeve 29 is preferably provided with spirally arranged partitions as at 30 for giving the air a whirling or twisting movement in entering the mixing chamber.

45 The movement of the thimble 28 and the needle valve sleeve 23 are so connected that when the suction of the engine, upon being speeded up, draws in such quantities of air

through the casing 26 as to lift the thimble 28, the needle 25 will be lifted correspondingly to introduce a large quantity of gasoline. This relative action of the parts is secured by providing a thimble 28 with a lateral projecting arm 31 which extends through a slot 32 formed in the casing 26, the said slot being made of ample length to permit the thimble to move to the desired extent. The outer end of the said arm 31 has adjustably secured thereto a loop 33, the said loop being adapted to have a sliding engagement with the upper end of an arm 34 which is secured to a rock shaft 35 which is journaled upon the framing of the carburetor. The upper end of said arm 34 preferably carries an anti-friction roller 36 which engages the said loop 33 without undue friction.

50 The rock shaft 35 is usually journaled in a projecting support 35^a arranged between the float chamber and the needle valve mechanism, and the said rock shaft at a point opposite said needle valve mechanism is provided with a bifurcated lever as 37. The ends of the bifurcated lever 37 are provided with inwardly projecting pins 38 which engage an annular groove 39 formed upon the outer surface of the sleeve 23. The rocking of the lever is thus capable of lifting the said sleeve. The said lever and the rock shaft 35 carrying the same are rocked whenever the thimble 28 is lifted by the suction of the engine, since the loop 33 is carried upwardly by the said thimble. It will be readily understood that by setting the loop 33 at a greater or less angle with respect to the thimble, the needle carrying sleeve 23 will be raised to a greater or less degree. The said loop 33 is therefore adjusted for supplying the right amount of gasoline for the higher speeds of the engine, and the introduction of said gasoline around the valve 25 will be controlled automatically by the movement of the thimble 105 28 which responds to the suction of the engine.

55 In the upper end of the mixing chamber 2 the usual throttle valve 40 is pivotally mounted, the stem of said valve extending outside of the casing and being provided with an operating arm 41 which may be connected with any portion of the automobile or other mechanism as desired so as to be within easy control of the operator.

60 In using the carburetor the float valve is manipulated in the usual way for introducing a greater quantity of gasoline than usual so that some of it will run into the pan 3 from the needle valve. In this way the carburetor is primed for starting the engine. When the engine has been started the needle valve will supply an ample quantity of gasoline for the running of the engine at low speed when the thimble is seated 110 120 125 130

upon the valve seat 27, and a corresponding amount of air being allowed to pass through the central portion of the thimble. When the engine is speeded up the suction thereof in drawing the gaseous mixtures through the carbureter will be correspondingly increased and the thimble 28 will be lifted from its seat for introducing a greater quantity of air through the casing 26 and the loop 33 will rock the shaft 35 so as to lift the needle 25 and introduce a correspondingly larger amount of gasoline for maintaining the right mixture within the chamber 2. It will be readily understood that after the parts are once adjusted for the low speed and the high speed action of the engine, the feeding of proportionate amounts of gasoline and air will be automatically accomplished.

20 What I claim is:—

1. A carbureter comprising a mixing chamber having inner and outer air inlet passages, a movable air controlling thimble mounted in said chamber and having a central air passage and adapted to control the passage of air through said inner and outer passages, the said outer passage having inclined air directing partitions therein, a gasoline valve mechanism projecting into said inlet, and adjustable means for connecting the same with the movable air controlling thimble for increasing the feed of gasoline when the air supply is increased.

2. A carbureter mechanism comprising a mixing chamber having an air inlet formed with a central air passage and an outer air passage surrounding the same, a movable air controlling thimble mounted in the inner passage and adapted to control the entrance of air through the outer air passage, a needle valve projecting downwardly into said thimble, and having connections with the gasoline supply, a lever mechanism adapted to open the needle valve to a greater or less degree, and means for adjustably connecting the said lever mechanism with the movable thimble whereby the valve is opened to supply an amount of gasoline corresponding with the amount of air introduced through the movement of said thimble.

3. A carbureter mechanism comprising a mixing chamber having an air supply passage-way, and a hollow movable thimble mounted therein capable of permitting the entrance of air through its hollow portion and also capable of controlling the entrance of additional air outside its hollow portion, a needle valve mechanism projecting into said air inlet comprising a tubular portion, 60 a sleeve mounted thereon, a tapering valve carried by said sleeve and adapted to enter the end of the tubular portion, a rock shaft for moving said sleeve, a lever for rocking said shaft, and an adjustable member carried by the thimble and capable of actuating the said lever for controlling the supply of gasoline through the valve mechanism in accordance with the movement of the thimble. 70

4. A carbureter mechanism comprising a mixing chamber, an air inlet casing mounted thereon, a movable hollow thimble arranged within said casing and controlling the air supply, a float chamber mounted upon said 75 casing for introducing a gasoline supply to the carbureter, a priming pan mounted on the float chamber, and having a passage-way formed therein communicating with said float chamber, a needle valve mechanism carried by the priming pan and connected with the said passage-way therein, said needle valve mechanism projecting into the air inlet of the carbureter, a valve carrying sleeve movably mounted on the valve 80 mechanism provided with a depending tapering needle for lifting or depressing the needle, an arm for rocking said shaft, an adjustable loop secured to the said thimble and engaging said arm, the movement of the 85 thimble in introducing more air under the suction of the engine thus being capable of operating the needle valve to introduce a corresponding quantity of gasoline.

In witness that I claim the foregoing I 95 have hereunto subscribed my name this 2nd day of February, 1911.
